Patented Jan. 11, 1910.

Application filed November 9, 1909. Serial No. 527,107. Term of patent $3\frac{1}{2}$ years.

To all whom it may concern:

Be it known that I, WILLIAM MURRAY MORTON, a subject of the King of Great Britain, and resident of Hastings Square, Darvel, Ayrshire, Scotland, have invented a new, original, and ornamental Design for Carpets, of which the following is a specification, reference being had to the accompanying drawing, forming a part thereof.

The figure is a plan view of a portion of a carpet embodying my new design.

The design comprises a filling formed of two large interlacing trellises, a broader

trellis formed of peonies and clematis and a smaller or undertone trellis formed of a treatment of the acorn. The border is a broad foliage band with a broad sprig margin.

I claim—

The ornamental design for a carpet, as shown, and described.
